UNITED STATES PATENT OFFICE

145,111

DESIGN FOR A UTILITY SHELF

Walter L. Willis, Detroit, Mich.

Application November 29, 1945, Serial No. 124,174

Term of patent 14 years

(Cl. D33—3)

To all whom it may concern:

Be it known that I, Walter L. Willis, a citizen of the United States, residing at Detroit, in the county of Wayne and State of Michigan, have invented a new, original, and ornamental Design for a Utility Shelf, of which the following is a specification, reference being had to the accompanying drawing, forming part thereof.

I claim:

The ornamental design for a utility shelf as shown.

WALTER L. WILLIS.
